UNITED STATES PATENT OFFICE.

BERTHOLD KÖRTING, OF HANOVER, GERMANY.

ROOM-HEATING PLANT.

No. 922,783.

Specification of Letters Patent.

Patented May 25, 1909.

Application filed April 2, 1908. Serial No. 424,887.

To all whom it may concern:

Be it known that I, BERTHOLD KÖRTING, a subject of the King of Prussia, German Emperor, and resident of 30 Am Schiffgraben, Hanover, in the Kingdom of Prussia, German Empire, gentleman, have invented certain new and useful Improvements in Room-Heating Plants, of which the following is an exact specification.

10 This invention relates to heating plants as applied to the heating of a plurality of rooms and its object is to effect the regulation of the heaters in the various rooms by means of the average temperature, in these rooms.

15 According to the present invention the heating fluid to the various heaters passes through a trunk pipe which is regulated by means of a valve actuated by a device operating by the expansion of a body under the 20 heating action of all the rooms supplied by said trunk pipe or by only some of these rooms, whereby the average temperature of all the rooms is utilized for effecting the regulation of a control device common to the 25 group of rooms. Any suitable heating fluid such as steam, water or air may be employed.

The heaters are preferably arranged in parallel between two trunk pipes or conduits.

30 The invention may be carried out in different ways for instance the expanding body may be air or a liquid or a solid expanding body may be used.

Referring now to the accompanying drawings: Figure 1 shows two rooms of a group in 35 which the expanding body employed is air. Fig. 2 is a detail of the actuating motor for the control device. Fig. 3 illustrates a modification in which a liquid is employed for the actuation of the control device. Fig. 4 shows 40 a modification in which the expansion of a solid body is utilized for the actuation of the control device. Fig. 5 shows a form in which only the heat of the middle rooms in a group is utilized for heating the expanding body.

45 In carrying the invention into effect according to the form shown in Fig. 1 the heaters in the rooms are supplied by a trunk pipe *b* from which branches *b'* lead and from the heater other branches *b''* lead to the exhaust pipe *b''*. The heating fluid is introduced to 50 the trunk pipe *b* by means of a nozzle *c*. The nozzle *c* is controlled by means of a valve *l* connected by a rod *k* to a bellows like motor *i*, the upper end of which is held fixed by 55 means of a screw or the like *i'* fixed in a cas-

ing *e* while the lower end of the bellows is free. Between the bellows or motor *i* and the walls of the casing *e* there is left a space through which air circulates. This circulating air is drawn from the rooms by means of 60 a pipe *g* provided with openings *h*, in the various rooms. The air circulates through the pipe *g* in the direction shown by the arrows and this circulation is induced by connecting the casing *e* by means of a pipe *d* with the 65 chamber of the nozzle *c*, whereby the nozzle *c* acts like an injector to induce the current of air through the casing *e*. The connecting rod *k* is preferably also articulated by means of suitable links as shown in Fig. 2 to a butterfly valve *m* in the pipe *d*.

The operation of this device is as follows: The hot air from the various rooms drawn through the openings *h* and the pipe *g* and laying around the exterior of the bellows 75 like motor *i* causes the expansion of the liquid in the bellows and thereby operates the valve *l* when the temperature reaches a given amount. In this way the regulation 80 of the temperature in the rooms is determined by the average temperature of these rooms, while obtaining at the same time a simple control and also a more even and regular heating of all the rooms than has hitherto been suggested.

85 In the case when steam is used and the injector in consequence forces a mixture of steam and air through the trunk pipe, it is advisable that the quantity of air drawn in by the injector nozzle *c* through the pipe *g* 90 should be as small as possible so as to prevent the quantity of air passing through the pipes *b* becoming too great. This is for the reason that such fresh air involves a loss of heat and a lowering of the temperature of the 95 fluid passing through the trunk pipe to the heaters. This quantity of air is therefore kept as small as possible by providing only a small conduit pipe *g* and further by regulating the flow through the pipes *g* by means of 100 the valve *m*. The valve *m* is so arranged with relation to the rod *k* that when the opening of the valve *l* is increased the valve *n* throttles the pipe *d*. It will be understood that the same relationships hold good 105 when air alone is supplied to the pipe *b*.

Instead of using an air stream from the several rooms for effecting the heating of an expanding body a liquid of high-expansion coefficient can be employed in conjunction 110

with the tube *g*. In this case it is immaterial whether the volumetric changes caused by changes in temperature act directly or through pistons on the motor *i*. The expansion of the liquid is of course as in the above described case proportional to and dependent on the average temperature of all the rooms. Such a form of heating device is shown in Fig. 3 and the rooms are provided 10 with containers *g* which are filled with the fluid, of high expansion coefficient. The tube *g* is closed and may also be filled with a fluid of these tubes may be filled only with air as desired. The tube *j* in this case connects directly with the upper end of a cylinder in which a piston is provided which acts upon fluid, contained in the lower part of the cylinder, and the bellows motor *i*. The lower end of the motor *i* is as before free to 15 move and is connected to the rod *k*. The rod *k* is connected to the valve *l* which controls the supply of heating fluid to the pipe *b*. It will be readily seen that in this form the expansion of the liquid in the containers 20 *g* will cause the closing of the valve *l*.

According to the form of regulating device shown in Fig. 4 the group of rooms are provided with a common regulating device or valve *l* which is operated by the expansion of 30 a solid body *i*. The solid body *i* is inclosed within a tube *r* which is made out of a material with a lower co-efficient of expansion than the rod *i*, so that when the tube *r* and the rod *i* are subjected to the heating action 35 of the rooms *p* the tube *r* expands in a direction of the arrow *x* while the rod *i* expands in the direction *y*. As this last expansion is greater than the first there is a resultant relative movement in the direction 40 of the arrow *y*, whereby the actuating rod *k* of the valve *l* is moved. The rod *i* is supported in guides *t* within the tube *r*, and holes *s* are provided for circulation of the air which thus comes in contact with the inner 45 expanding rod. In Fig. 5 there is illustrated a form in which the end rooms *p* are switched off and only the middle rooms are employed for the purpose of obtaining the average temperature of the group.

50 Having thus fully described the nature of my said invention what I desire to secure by Letters Patent of the United States is:—

1. In combination in a heating plant for a plurality of rooms, heaters in the various rooms, a common control device for the heaters in a group of rooms, an actuating expansion device for said control device, said actuating device being subjected to the temperature of the air in a plurality of the rooms 55 to be heated.

2. In combination in a heating plant for a plurality of rooms, heaters in the various rooms, a common control device for the heaters in a group of rooms, an actuating ex-

65 pansion device for said control device, said actuating device being subjected to the heating action of the air in all the rooms.

3. In combination in a heating plant for a plurality of rooms, heaters in the various rooms, heating fluid supply pipes to said 70 heaters, a trunk conduit from which said supply pipes lead, a control valve in the trunk pipe, an actuating expansion device for said control valve, said actuating device being subjected to the heating action of the 75 air in a plurality of the rooms the temperature of which is to be regulated.

4. In combination in a heating plant for a plurality of rooms, heaters in the various rooms, hot fluid supply pipes to said heaters, 80 a trunk pipe from which said supply pipes lead, a control valve in the trunk pipe, an actuating expansion device for said control valve, said actuating expansion device comprising a fluid conduit extending for part of 85 its length through a plurality of its rooms and a fluid motor receiving its motive power from the fluctuating energy of the fluid in the conduit in consequence of the temperature alterations in the rooms.

90 5. In combination in a heating plant for a plurality of rooms, heaters in the various rooms, hot fluid supply pipes to said heaters, a trunk pipe from which said supply pipes lead, a control valve in the trunk pipe, an actuating expansion device for said control valve, said actuating expansion device comprising a conduit having openings therein to the various rooms, a motor, a chamber containing said motor and through which the 95 air from said conduit passes, and means for causing an air circulation through said conduit and chamber.

100 6. In combination in a heating plant for a plurality of rooms, heaters in the various rooms, hot fluid supply pipes to said heaters, a trunk pipe from which said supply pipes lead, a control valve in the trunk pipe, an actuating expansion device for said control valve, said actuating expansion device, comprising a conduit passing through and having 105 openings to the various rooms, a chamber with which said conduit communicates, an expandible closed bellows within said chamber and fixed at one end, a connection from the free end of said bellows to the control valve, an injector on the trunk pipe, and a pipe leading from the bellows containing 110 chamber to the injector.

115 7. In combination in a heating plant for a plurality of rooms, heaters in the various rooms, hot fluid supply pipes to said heaters, a trunk pipe from which said supply pipes lead, a control valve in a trunk pipe an actuating expansion device for said control valve 120 said actuating expansion device comprising a conduit passing through and having openings to the various rooms, a chamber with 125

which said conduit communicates, an expandible closed bellows within said chamber and fixed at one end, a connection from the free end of said bellows to the control valve,
5 an injector on the trunk pipe, a pipe leading from the bellows containing chamber to the injector, and a control valve on said pipe and operated by the bellows.

In witness whereof I have hereunto set my hand in the presence of two witnesses.

BERTHOLD KÖRTING.
